BUILDING STRUCTURE

Frederick M. Venzie, Philadelphia, Pa.

Application September 20, 1930, Serial No. 483,188
Renewed April 6, 1933

3 Claims. (Cl. 72—118)

This invention, generally stated, relates to a building structure and has more especial relation to a novel form of clip for supporting plaster boards as used in ceiling, partition, and wall constructions, and has more especial relation to a clip formed of wire in contradistinction to stamped metal clips.

The leading object of the present invention may be said, therefore, to reside in the provision of a novel form of wire clip whereby unskilled labor may more rapidly and efficiently erect ceiling, partition, and wall constructions in which plaster boards are employed, thereby to reduce building costs.

15 A further object of the present invention may be said to reside in the provision of a wire clip for attachment to beams which may be I-beams, T-beams, channel irons, and the like, said clip being provided with rounded corners to prevent fracture of the plaster boards in the assembly of a ceiling, partition, or wall, and also to facilitate rapid assembly.

20 A still further object of the present invention is to provide a novel form of wire clip which may be fitted to beams arranged horizontally or vertically and which may be I-beams, T-beams, channel irons, and the like for the support of plaster boards.

25 A still further object of the present invention is to provide a wire clip of the character stated which is arranged for coupling together the meeting edges of plaster boards.

30 A still further object of the present invention is to provide a clip of the character stated which 35 may be more economically manufactured than present types of clips stamped from metal.

35 Other and further objects of the present invention reside in the provision of the general arrangement, combination, and connection of novel 40 wire clip parts for attaining the results sought by the foregoing objects.

The invention consists of the novel construction hereinafter described and finally claimed.

45 The nature, characteristic features and scope of the invention will be more fully understood from the following description taken in connection with the accompanying drawing forming part hereof, and in which:

50 Fig. 1 is a view partly in elevation and partly in section of a building structure in which plaster boards are connected together and with respect to channel irons by means of my novel form of wire clip;

55 Fig. 2 is a fragmentary view in front elevation

of the parts illustrated at the lower portion of Fig. 1;

Fig. 3 is a view in section taken upon the line 3—3 of Fig. 2;

Fig. 4 is a view in perspective of the wire clip 60 shown at the left hand side of Figs. 2 and 3; and

Fig. 5 is a similar view of the novel form of wire clip shown at the right hand side of Figs. 2 and 3.

For the purpose of illustrating my invention I have shown in the accompanying drawing two forms thereof which are at present preferred by me, since the same have been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring now to the drawing in detail, and with especial relation to Figs. 1, 2, and 3, the reference numeral 10 designates a channel iron as used in floor and ceiling construction, and the reference numeral 11 designates a channel iron as used in partition and wall constructions. Obviously instead of channel iron the members 10 and 11 may be I-beams, T-beams, or members of angle iron construction. Obviously the channel irons 10 are horizontally disposed and the channel irons 11 vertically disposed. The reference numeral 12 designates conventional plaster boards, and it is to be understood, in the connection, that instead of plaster boards, slabs of cementitious material may be used, as is well understood in the art. The reference numeral 13 designates plaster boards as employed in forming a partition or wall. The plaster boards may be supplanted by slabs of cementitious material, if desired. However, for the purposes of illustration, plaster boards are disclosed and it will be understood that conventional plaster boards are enveloped in a felt paper covering which readily fractures. In order to support the plaster boards 12 with respect to the channel irons 10, use is made of the wire clip best seen in Fig. 4.

45 In order to couple together adjacent meeting faces of the plaster boards use is made of the wire clip best seen in Fig. 5. Similar wire clips are employed in connection with the plaster 105 boards 13 with respect to each other and with respect to the channel iron 11.

Taking up first the wire clips used for securing the plaster boards with respect to the channel irons 10 and 11, and with especial relation to 110

Fig. 4, each clip comprises a continuous piece of wire bent to provide opposed elongated loop-like members 14 and 15 interposed between which is a loop-like member 16 arranged at right angles with respect to the members 14 and 15. The member 16 is arranged to engage around a channel iron 10 or 11, and for this purpose the members 14 and 15 are spaced apart to provide an entrance groove 17, so that by passing 10 the entrance groove 17 with respect to a channel iron and moving the wire clip around the channel iron the member 16 is caused to become relatively interlocked with respect to a channel iron, as clearly illustrated in Fig. 3.

15 Taking up now the wire clip shown in Fig. 5, the same is employed to relatively interlock adjacent plaster-boards both in ceiling, partition, and wall constructions. This clip may be formed of a continuous piece of wire bent to form opposed plaster-board accommodating portions arranged in the same plane, each of said portions comprising parallel, spaced end members 17 and 18, each of said members 17 and 18 terminating in opposed, spaced members 19 and 20 arranged 20 at right angles to the members 17 and 18. Thus formed the members 17-18 and 19-21 provide entrance spaces to receive adjacent ends of the plaster-boards, as clearly shown in Fig. 2. The members 19 and 20 are connected by the inclined 25 strand 21 of the wire used in the formation of the clip.

From the above description it is apparent that the wire clip shown in Fig. 4 may be employed for supporting either ceiling, partition, or wall 30 plaster-boards with respect to supporting means, as channel irons and the like, and that the wire clip shown in Fig. 5 may be employed for coupling together adjacent ends of plaster-boards as supported from said supporting means. In 35 the connection it is to be noted that the wire employed in shaping the respective clips is so bent that rounded corners 22 are present between the various plaster-board receiving members to prevent abrasion of the paper covering of the 40 plaster-boards in introducing the plaster-boards with respect to the various plaster-board receiving spaces before described. After the plaster-boards are properly supported the usual coat of plaster 23 is applied, see Fig. 1. In the connection 45 it is to be noted, as clearly shown in Fig. 2, that the adjacent ends of the plaster-boards may be slightly spaced one from another to provide plaster-receiving spaces 24 by reason of which the plaster coating may seep between the 50 adjacent ends of the plaster-boards to form a bond therebetween. Such spacing is obtained due to the fact that in bending of the wire to form plaster-board accommodating members, that cross-portion 25 of the clip shown in Fig. 5 55 and those cross-ports 26 and 27 of the clip shown in Fig. 5 are arranged to lie between adjacent plaster-board ends, as clearly shown in Fig. 2. This arrangement is usually employed in walls and partition structure where plaster is used upon opposite sides of the plaster-boards or slabs. In ceiling constructions, however, I prefer to have adjacent end and side edges of the plaster-boards or slabs abut, and in such case I drive the boards or slabs by means of a 60 hammer so as to cause the wire parts described 65 to embed in the friable portion of the board or

slab and thus eliminate any cracks between the boards or slabs. It is important that such cracks be absent in some instances, as in ceilings, since after plaster is applied to the faces of the boards or slabs upon one side only an outline of the joints appears. The terminals of the wire forming the clips may be brazed, soldered, or the like where they meet with the body portions of the clips, if desired.

The securing device or wire clip as above described has the attributes of lightness, pliability, strength, and may be manufactured quite inexpensively and lends itself readily and conveniently to manufacture from a single piece of wire. The body is of skeleton-like configuration, having spaced, plaster-board supporting members arranged in parallel planes. The clip occupies but very little space, and therefore is inconspicuous in use, and in one of its forms requires no auxiliary means of attachment to a support or stud.

What I claim is:

1. In a building construction of the character stated, in combination, a fixed angle-iron for supporting ceiling, partition, and like units, including plaster-board and/or equivalent slab-like members, means for detachably connecting said members with respect to said angle-iron, said means including a clip comprising an integral, skeleton-like device consisting of a wire bent first in duplicate parallel series in one plane to engage around said angle-iron and thereafter bent in duplicate parallel series in a plane at right angles to said first mentioned series of wires in a plane to co-operatively receive the ends of said ceiling, partition or/and like units, and a clip 100 comprising an integral, skeleton-like device consisting of a single wire bent in opposite directions in the same plane to co-operatively receive adjacent, meeting ends of said units.

2. In a building construction of the character 105 stated, fixed angle-irons which intersect one another vertically and horizontally considered for supporting ceiling, partition, and like units, plaster-boards arranged in abutting relation with the inner flanges of said angle-irons, clips each 110 comprising an integral, skeleton-like device consisting of a wire bent first in spaced duplicate parallel series in one plane to engage around said angle-irons including said flanges, and thereafter bent in spaced duplicate parallel series in 115 a plane at right angles to said first mentioned series of wires in a plane to co-operatively receive the ends of said plaster-boards, and clips formed of wire bent in opposite directions to co-operatively receive adjacent meeting ends of 120 said plaster-boards.

3. In a building construction of the character 125 stated, fixed supports for carrying ceiling, partition, and like units; plaster boards arranged in abutting relationship with said supports; clips, 130 each comprising an integral skeleton-like device consisting of a wire bent first in spaced duplicate parallel series in one plane to engage around said support, and bent in spaced duplicate parallel series in a plane at right angles to said first mentioned series of wires in a plane to co-operatively receive the ends of said plaster boards, a portion 135 of said last named series lying in the plane of the face of the support against which said plaster boards abut.

FREDERICK M. VENZIE.
